C. E. KIMBALL

LIMIT STOP AND GOVERNOR FOR ELEVATORS

Filed Mar. 21, 1921

INVENTOR,
CHARLES E. KIMBALL
BY *Charles E. Kimball*

ATTORNEY.

UNITED STATES PATENT OFFICE.

CHARLES E. KIMBALL, OF COUNCIL BLUFFS, IOWA.

LIMIT STOP AND GOVERNOR FOR ELEVATORS.

Application filed March 21, 1921. Serial No. 454,231.

To all whom it may concern:

Be it known that I, CHARLES E. KIMBALL, a citizen of the United States, residing at Council Bluffs, in the county of Pottawattamie and State of Iowa, have invented a new and useful Limit Stop and Governor for Elevators, of which the following is a specification.

My invention relates to improvements in limit stops and governors for elevators in which the movements of the elevator car and counter-balancing weights are applied to throw off the current and apply a braking mechanism: and the objects of my improvements are, first, to provide a simplified limit and slack cable control of the operating current and winding machine brake; second, to utilize such limit control for governing any excessive speed of the elevator car or weights; third, to so apply such limit stop and regulator to both the weights and the car of an elevator and to greatly simplify the construction of the class of elevator governors and limit stops.

I attain these objects by the mechanism illustrated in the accompanying drawing, in which—

Figure 1 is a diagrammatic illustration of an elevator car, counter-balancing weights, connecting cables, brake drum, and line switch; Fig. 2, is a side elevation of the governor sheave; Fig. 3, is a detailed elevation and cross-section of the governor sheave; Fig. 4, is a diagram of the operation of switch lever; Fig. 5, is a diagram of operation of brake lever.

Similar letters refer to similar parts throughout the several views.

b, is the ordinary cage of an elevator; *s*, the overhead sheave; *a*, the counter-balancing weights; *r*, and *r'*, the connecting cables. A sheave *c*, is suitably suspended by rope or cable *e*, and over the suspended sheave *c*, a rope *k*, passes from a weight *n*, resting on the cage *b*, to a similar weight *m*, resting on the counter-balance weights, *a*. By means of suitable sheaves, as *t* and *u*, the rope or cable, *e*, may be carried to any convenient place. The rope or cable *e*, engages a part *h*; the part *h*, consists of a movable bar or piece having projections which pro-

jections on the part, *h*, engages at 1, a lever 5, holding closed the line switch, 6, and engages at 2, the lever *j*, of the brake *p p'* on the brake-drum, *y*; the usual spring *f*, operates the brake elements, *p p'*, upon the brake-drum, *y*; the lever *j*, in connection with the link, 7, is adapted against the spring *f*, to hold the brake elements *p p'* in an open position or off, when the lever 5, holds the switch 6, closed; the hinged connection of *j* and 7 are placed off center with the pivot of the link 7 and the lever *j* respectively, in the brake elements *p p'* when the switch is closed and the brake released against the spring, *f*. The weights, *n* and *m*, rest respectively on the cage *b*, and the counter-balance weights *a*. For steadyng the motion of the apparatus, the lever *d*, hinged to the proper supporting element *g*, may be used to prevent undue oscillation of the sheave, *c*; the usual safety catch may be supplied having the lever 3 on the cage *b*, and having the lever 4 on the weights *a*.

The sheave, *c*, when used as a speed governor has two centrifugally disposed weights, *w w'*, each weight held in normal position by springs, *v v'*; the weights *w* and *w'* being adapted by suitable hinging to be centrifugally operated against the springs *v* and *v'*; a braking means, *x*, adapted to move eccentrically with the sheave, *c*, has a stop or pin, *z*, adapted to engage the weights, *w* and *w'*, when by centrifugal force the weights, *w* and *w'* are thrown out of their normal position as held by the springs, *v* and *v'*, respectively. Upon the weight *w* or *w'*, engaging the stop or pin, *z*, the brake, *x*, is pressed onto the cable or rope, *k*, over the sheave, *c*.

When the part *h*, moves either sufficiently downward or upward, the levers 5 and *j*, are released from their engagement with *h*, at 1 and 2. A suitable rod, 8, with suitable nut, 9, extends slightly beyond the limit of travel of the cage *b*, and similarly the rod *o*, with suitable nut, 10, extends slightly beyond the limit of travel of the counter balanced weights, *a*. The rod, 8, engages the weight *n*, and the rod *o*, engages the weight *m*. The rod 8, may be arranged to engage the safety catch lever 3, on the cage *b*, and the rod *o*,

engages similarly the safety catch lever 4, on the counter-balanced weights a . The brake-drum y , is attached to the usual winding mechanism for moving the cage b , up 5 and down the connecting mechanism not here being shown.

The principal part of my invention consists of the use of a weighted cable or rope over a suspended sheave to operate a line 10 switch and elevator brake. When the elevator cage b , runs beyond its limit of travel the rod 1, will be moved upwards lifting the weight n , from the cage b ; the rope or cable k , will thus be lengthened with respect to 15 the distance from the cage b , to the counter-balanced weights a , and due to the pressure of the spring f , on the brake p, p' , the part h , engaging the lever j , will move downwardly as the sheave c , moves upwardly. The movement 20 of the lever j , downward puts the brake p, p' , on and similarly the movement of the lever 5, engaging h , at 1, moving downward allows the line switch 6, to drop open thus the main line current will be cut off and the 25 brake applied to stop the movement of the cage b , connected by the cable r , and the counter-balanced weights a , connected by the cable r' . Similarly if the cage reaches its 30 highest point the counter-balanced weights a , will reach its limit, the rod o , will be raised lifting the weight m , from the counter-balance weights a , allowing the sheave c , to move upwardly and the part h , downwardly throwing out the line switch 6, and throwing 35 the brake p, p' on. In a similar manner the device is effective as a slack cable stop or governor. Whatever causes a change of relative distance between cage and counter-weights will move the sheave c , and 40 operate the brake p, p' , and line switch 6. In limit structures of this kind the engagement of the part h , with the lever 5, controlling the line switch 6, and the lever j , controlling the brake p, p' , should be such 45 that it can only be replaced by the operator by going to the brake lever j , and the switch lever 5, and operating the same by hand.

The limit stop device herein described utilizing the sheave c , may also have combined with it the usual governor facilities and safety catches. For this additional purpose the weights w and w' are provided in the sheave c , held in normal position by the respective spring v or v' . When the cage 50 moves beyond a fixed limit of speed by centrifugal force one of the weights as w or w' will be thrown out of its normal position as held by the springs v or v' , and will engage the stop z , which will operate the brake x , 55 clamping the cable or rope k , to the sheave c . When the rope or cable k , is clamped in the sheave c , the part h , will be thrown upward until the lever 5, allows the line 60 switch 6, to open and the brake p, p' , to go on,

The holding of the cable k , by the brake x , 65 will also operate the safety catch lever 3. Similarly if the cable r , should break and the cage b , descend beyond its limit of speed and likewise the counter-balanced weights a , descend, the cable or rope k , will pull the 70 sheave c , and throw the part h , upward, throw out the line switch 6, and throw on the brake p, p' . The rod 8, will operate the safety catch lever 3, and the rod o , will operate the safety catch lever 4. 75

I am aware that prior to my invention centrifugal governors with cables running from the cage over a movable sheave back to the cage have been employed for the operation of safety catches. 80

But what I claim and desire to secure by Letters Patent, is:

1. The combination of a moveable sheave; a weighted cable over the same, one end loosely engaging an elevator cage and the other the counter-balance weights of said elevator, and connections from said moveable sheave engaging a line switch and brake. 85

2. In a limit device for elevators, a moveable sheave, a cable passing over it weighted at each end, said weights supported respectively on the cage and counter-balanced weights of the elevator and means for lifting said weights when the elevator cage or counter-balanced weights pass their limit of travel, and connections between said sheave and a line switch and brake. 90

3. In a limit device and governor for elevators, a moveable sheave; a cable passing over said sheave, weighted at both ends, said weights resting respectively on the cage and counter-balanced weights of the said elevator with means for lifting the said weights when the cage or counter-balanced weights pass their limit of travel; centrifugal weights and a brake on said moveable sheave and connections between said sheave and a line switch and a brake. 100

4. In a regulating device for elevators; a suspended sheave, connections between said sheave, and a line switch of said elevator, an elevator braking mechanism, whereby a vertical movement of said sheave in either direction operates to apply the brake and open the line switch; a weighted cable on said sheave; one weighted end resting on the cage of elevator, the other weighted end resting upon the counter-balanced weights; rods engaging said weights and extending beyond the limit of travel of the said cage and counter-balance weights adapted to be moved when said cage or counter-balance weights pass beyond their limit of travel; centrifugal weights in said sheave; a brake on said sheave adapted to be operated by the centrifugal motion of said weights and springs holding said centrifugal weights in normal position. 110

5. In a regulating device for an electric elevator; a sheave having centrifugal weights, springs, and a brake adapted to be moved by the operation of the said centrifugal weights; a cable over said sheave; weights on each end of said cable resting respectively on the cage of the elevator and on the counter-balance weights; rods engaging said weights; safety catches engaging said rods of said cage and counter-balance 10 weights and connections between said sheave, the line switch and a brake on said elevator.

CHAS. E. KIMBALL.
